BOTTLE

Hans G. Stenger, Lambertville, Mich., and William E. Fillmore, Toledo, Ohio, assignors to Owens-Illinois Glass Company, Toledo, Ohio, a corporation of Ohio

Filed July 19, 1960, Ser. No. 61,420

Term of patent 14 years

(Cl. D58—8)

Fig. 1 is a top plan view of a bottle showing our new design.

Fig. 2 is an elevational view thereof.

Fig. 3 is an elevational view with the bottle rotated 90° from the position shown in Fig. 2.

The side not shown is the same as the side shown and the front is plain.

The drawing is shaded to show contrasting colored areas.

We claim:

The ornamental design for a bottle, substantially as shown and described.
